UNITED STATES PATENT OFFICE.

JOHN E. KILKER, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

STEAM-TURBINE.

1,193,902.

Specification of Letters Patent. Patented Aug. 8, 1916.

Application filed May 21, 1915. Serial No. 29,487.

To all whom it may concern:

Be it known that I, JOHN E. KILKER, a citizen of the United States, residing at Chicago, in the county of Cook and State of Illinois, have invented a certain new and useful Improvement in Steam-Turbines, of which the following is a specification.

My invention relates to steam turbines and has for its object to provide means whereby the engine may be regulated, or steam be cut out in the event of the use of a regulating device which for any reason has become defective.

The invention in the preferred form is illustrated in the accompanying drawings wherein—

Figure 1 is an elevation of a turbine with parts broken away to show other parts in operative position: Fig. 2 is a similar view with parts broken away to show the engine cut out.

Like parts are indicated by the same letter in both of the figures.

A is the casing which incloses all of the parts. A shaft B runs from end to end of the machine carrying at the right the dynamo or other driven part. It is mounted in suitable bearings.

C is a diaphragm about the shaft with packing grooves C¹ and a spring groove C² to receive one end of the spiral spring C³ which encircles the shaft. The other end of this spring bears against the ball-bearing device C⁴, the inner ring of which is rigid on a reduced portion of the shaft B and the outer ring of which bears upon the collar C⁵ which is rigidly secured to the diaphragm C. Thus the spring is received into a pocket and tends always to hold the shaft toward the right, that is in operative position as illustrated in Fig. 1.

D is the left-hand end of the shaft B in a boss D¹ on the turbine wheel D² and there is a clearance space D³ so that the shaft may be moved a certain distance toward the left if the spring C³ be sufficiently flexed.

E, E¹ are the buckets normally in opposition to the nozzles E¹ to which the steam is led through the passage E² from the valve chamber E³. The steam enters this chamber from the opening E⁴ which is controlled by the valve E⁵. I do not dwell upon the details of the construction of this valve because that forms no part of the present invention.

The valve has a stem F, and is encircled by a spring F¹ which tends to keep it off its seat. It is connected to one arm of a lever F² which is pivoted at F³ and has a roller F⁴ which engages one end of a lever F⁵ which is pivoted at F⁶ and is bifurcated, its two ends encircling the ring F⁷ and pivoted thereto at opposite sides by pivots F⁸. The details of this construction form no part of the present invention. The ring F⁷ bears against one end of the sleeve G which surrounds the shaft and is provided with a spring G¹ connected to the adjustable collar G² controlled by a series of screws G³. This spring is adjusted so as to tend to force the sleeve toward the left.

J is one of a series of governor weights having each a pivotal bearing J¹ against the wheel, a weight arm J² and a toe J³ which lies under the end of the sleeve G. These several parts form no part of the present invention, but they are described sufficiently to serve as an explanation or description of one form of an apparatus which contains my invention.

It will be understood that I do not wish to limit my invention to the use of the particular device here shown except to the extent indicated in the appended claims.

The use and operation of my invention are as follows: Assuming a structure shaped as here shown, it is evident that when for any reason the turbine wheel begins to rotate rapidly the governor weights will be rocked on their pivots, the toe of the governor levers will force the sleeve G toward the right against the action of the spring G¹ and this will move the ring F⁷ toward the right and rock the lever F⁵ on its pivot. This in turn will rock the lever having the arms F² and F⁴ and force the valve stem upwardly to seat the valve. In the meantime the parts are all held in general operative position by the spring C³. If now the valve fails to work, if, for example, it has been so worn that the steam continues to pass through the valve after the governor has performed its entire function, or if there be an obstruction between the valve and the seat so that the governor can not completely seat the valve and cut off the steam, then if the load be cut off the wheel will continue to rotate under such restricted supply of steam until the operation becomes dangerous or destructive. With the

100
105
110

arrangement here shown, however, as soon as the governor weights have operated to move the sleeve G as far to the right as possible, if the speed increases or continues, 5 the point J¹ ceases to be the fulcrum of the governor weight, the point J³ becomes such fulcrum and the wheel is forced to the left into the position indicated in Fig. 2 where the buckets are out of register with the nozzles and the steam has been cut off from the buckets. The wheel therefore must tend to stop and the operator will speedily observe 10 that something is the matter and will investigate and restore the parts to their 15 proper condition.

I claim:

1. A turbine wheel in combination with a steam supply nozzle, a valve to control the supply of steam thereto and a governor responsive to the speed of the wheel to operate the valve and to move the wheel to reduce the supply of steam to the wheel. 20
2. A turbine wheel in combination with a steam supply nozzle, means for holding the turbine wheel yieldably in normal relation to the nozzle, a governor responsive to the speed of the wheel, a valve controlled by said governor to control the supply of steam, means responsive to the operation of the governor for moving said wheel out of the normal relation with the nozzle. 25
3. The combination with a turbine wheel and steam supply nozzle of a valve for controlling the supply of steam to the nozzle, a governor operated by the wheel for controlling said valve, and means responsive to the operation of the governor and operative after the manipulation of the valve by the governor for displacing the wheel out of 30 register with the nozzle. 35
4. The combination with a turbine wheel and steam supply nozzle of a valve control- 40

ling it, a governor actuated by the wheel to control the valve, and a connection between the governor and the wheel to laterally displace the wheel in response to excess rotational speeds thereof to throw the wheel out of line with the nozzle. 45

5. The combination with a turbine wheel and steam supply nozzle of a valve for controlling the supply of steam to the nozzle, a governor operated by the wheel for controlling said valve, and means responsive to the operation of the governor and operative after the manipulation of the valve by the 50 governor for displacing the wheel out of register with the nozzle, and yielding means for normally holding the wheel in line with the nozzle. 55

6. The combination with a turbine wheel 60 and steam supply nozzle of a valve controlling it, a governor actuated by the wheel to control the valve, and a connection between the governor and the wheel to laterally displace the wheel in response to excess rotational speeds thereof to throw the wheel out of line with the nozzle, and yielding means for normally holding the wheel in line with the nozzle. 65

7. The combination with a turbine wheel 70 and steam supply nozzle of a valve for controlling the supply of steam to the nozzle, a governor operated by the wheel for controlling said valve, and means responsive to the operation of the governor for displacing the wheel out of register with the nozzle. 75

In testimony whereof, I affix my signature in the presence of two witnesses this 18th day of May, 1915.

JOHN E. KILKER.
